(57) CLAIM

The ornamental design for an armoire, as shown and described.

DESCRIPTION

FIG. 1 is a front elevational view of the armoire of my design;

FIG. 2 is a front elevational view thereof, with the doors shown in an open position;

FIG. 3 is a right side elevational view of the armoire of FIG. 1, the left side being a mirror image; and,

FIG. 4 is a top plan view of the armoire of FIG. 1.

The back and bottom views form no part of the claimed design.
